United States Patent Office

Des. 229,136
Patented Nov. 13, 1973

229,136

CHAIR

Thomas Winrow, Naperville, Ill., assignor to Mohasco
Industries, Inc., Amsterdam, N.Y.

Filed Dec. 17, 1971, Ser. No. 209,491

Term of patent 14 years

Int. Cl. D6—01

U.S. Cl. D6—71

The figure is a perspective view of a chair illustrating my new design. The back of the chair is conventionally plain while the side not shown is substantially identical to the side shown.

I claim:

The ornamental design for a chair, as shown and described.
